ELECTROMECHANICAL CONTROL SYSTEM

Kurt Singer, Burbank, Calif., assignor to Radio Corporation of America, a corporation of Delaware

Application June 20, 1939, Serial No. 280,031

6 Claims. (Cl. 179—100.3)

This invention relates to electrical control circuits and particularly to a feedback circuit arrangement for neutralizing undesired resonance characteristics in an electrical element.

In the art of sound recording, a well known method of and system for modulating a light beam being impressed upon a sound track area of a film is by the use of a galvanometer having a moving armature which tilts a mirror for deflecting the beam transversely to the film. The armature of the galvanometer is actuated by a magnetic field produced by a coil connected to the output of the speech or audio-frequency amplifying equipment which, in turn, may be connected to a microphone or other translating device, such as a phonograph pickup or the like. The armature of the galvanometer is usually tensioned, which produces a mechanical resonance at one or more frequencies, while there may frequently be an electrical resonant point somewhere in the system.

In view of these conditions, the deflection of the mirror is not uniform for the same current input from the speech amplifying equipment at varying frequencies, thus causing distortion of the sound being impressed upon the film. For optimum operation, the frequency-response characteristic of the galvanometer should be flat over the entire frequency range.

The present invention minimizes the effect of any distortion of the galvanometer frequency characteristic and thereby permits of greater tolerances in the manufacture of the galvanometer and the electrical circuit used therewith. In brief, the operation of the invention is that voltages in accordance with the frequency-response characteristic of the galvanometer are generated, and these voltages are amplified, reversed in phase and fed back into the speech input amplifying system. Since the feedback voltages are in phase opposition to the original voltages, a cancellation or neutralization will take place in the electrical circuit, thereby producing the flat frequency characteristic desired.

The generation of the feedback voltages is accomplished by intercepting a portion of the light beam of the sound recording system, these light waves being impressed upon a photoelectric cell. By this arrangement, any galvanometer having any particular type of frequency-response characteristic may have its response corrected regardless of the construction of the galvanometer itself.

The principal object of the invention, therefore, is to improve the operation of an electro-mechanical device.

Another object of the invention is to maintain a constant relationship between frequency input and the response of a moving element actuated by electrical currents.

5 A further object of the invention is to reintroduce into an amplifying system voltages directly proportional to movements caused by electrical currents originating from this amplifying system.

A further object of the invention is to provide a feedback circuit for a sound recording galvanometer wherein the feedback voltages are obtained by intercepting light beam variations produced by the galvanometer.

15 Although the novel features which are believed to be characteristic of this invention are pointed out with particularity in the claims appended herewith, the manner of its organization and the mode of its operation will be better understood by referring to the following description read in conjunction with the accompanying drawing forming a part thereof, in which

Figure 1 is a diagrammatic arrangement of a sound recording system embodying the invention; and

25 Figure 2 is a graph showing characteristics of the system and the manner of its operation.

Referring now to Fig. 1, a microphone 5 feeds an audiofrequency or speech input amplifier 6. The output of the amplifier 6 is fed into a galvanometer 8 of any well known type having a mirror 10 which tilts or vibrates in accordance with the amplitude and frequency of the sound waves to be recorded. The light source of the apparatus comprises a lamp represented by a filament 12, the light therefrom being projected through a lens and mask unit 13 to the mirror 10 of the galvanometer. Reflected light from the mirror is projected to a film 15 through an optical slit assembly 16. A well known type of sound recording system so represented is disclosed and claimed in U. S. Patents 2,102,776; 2,102,777 and 2,102,778.

30 To obtain the voltages produced by the actual response of the galvanometer as represented by the movements of the mirror 10, a reflector 18 is placed so as to intercept light between the mirror 10 and the assembly 16. This reflector is so positioned that it does not interfere with the portion of the beam being projected to the film 15 but does intercept the outer portions of the beam which vary either in intensity or area in the same relationship as the beam being impressed on the film.

35 The light reflected from mirror 18 passes through a slit 19 and by means of a lens 20 is

projected as a variable intensity beam upon the cathode of a photoelectric cell 22. Thus the light reaching the cell 22 will vary in accordance with the vibrations of the mirror 10 and will create at the input to a feedback amplifier 24 voltages directly proportional to the movements of the mirror 10. The output of the feedback amplifier passes through a pair of series connected phase and amplitude adjusting circuits 25 and 26, such as illustrated in U. S. Patent 2,011,566 of August 10, 1935. The arms of the bridge comprise impedance elements such as illustrated in this patent and are for the purpose of producing a phase shift in the output currents of the amplifier 24. The output of the phase adjusting circuits is impressed upon the input of the amplifier 6, as shown.

To illustrate the operation of the feedback circuit just described, reference is made to the graph of Fig. 2 wherein curve A shows a typical galvanometer frequency characteristic without the feedback circuit 18-26. It will be noted that curve A is not a straight line as shown by curve B, curve B being an ideal characteristic. It will also be noted from curve A that the frequency response is slightly higher in the lower frequency region, lower in the middle frequency region and particularly high in the upper frequency region. This last peak is caused by mechanical resonance. However, with the particular feedback circuit of applicant's invention, it is not only possible to eliminate the high resonance peak occurring at around nine thousand cycles, but also the smaller variations in response.

On the graph shown in Fig. 2 is a dotted curve C. Since the response of the galvanometer is shown by curve A and the voltage generated in the cell 22 is directly proportional to the movements of the mirror 10, a voltage proportional to curve A will be impressed upon the amplifier 24 from cell 22. Since this voltage is reversed in phase and fed back to the input of amplifier 6, its effect upon the input to the galvanometer is similar to a voltage input having a frequency characteristic as shown by curve C. Thus, curve C is used only in an illustrative manner to show the method of flattening out the frequency characteristic of the galvanometer frequency response.

Other feedback circuits are known wherein a special galvanometer construction utilizes a second coil on the galvanometer armature wherein are generated the feedback voltages. The present correcting system, however, is applicable to any type of galvanometer construction and will accomplish the same overall correction as where the galvanometer is particularly constructed for generating the feedback voltages.

I claim:

1. In a resonance correcting system for an electro-mechanical device, the combination of a mov-

able element, a light deflector actuated by said element, means for impressing currents of varying amplitudes and frequencies on said device for actuating said movable element, means for intercepting light deflected by said light deflector, means for translating variations of light caused by said deflector into voltages corresponding therewith, and means for reintroducing said voltages into said current impressing means.

2. A resonance correcting system in accordance with claim 1 in which said last-mentioned means includes an amplifier and phase and frequency response adjusting networks.

3. In a sound recording system, the combination of means for producing a light beam, means for projecting said beam to a film, a mirror for vibrating said beam with respect to said film, a movable armature for actuating said mirror, an inductance surrounding said armature, means for impressing currents having varying amplitudes and frequencies on said inductance for moving said armature and said mirror, means intermediate said mirror and said film for translating light deflections caused by said mirror into corresponding voltages, and means for reintroducing said voltages into said current impressing means, said last-mentioned means comprising a network of phase and frequency characteristic adjusting elements.

4. The method of neutralizing mechanical and electrical resonance peaks in an electro-mechanical device for modulating light comprising generating with a portion of the light modulated by said device voltages corresponding to said light variations, and reintroducing said voltages into said electro-mechanical device after a phase reversal thereof.

5. In a sound recording system, the combination of means for producing a light beam, means for projecting said beam upon a film, a mirror adapted to deflect said beam with respect to said film, an armature adapted to move said mirror, a coil for producing a magnetic field in which said armature is located, an amplifier connected to said coil for impressing currents of different amplitudes and frequencies on said coil, means for translating light variations caused by said mirror movements into corresponding voltages, a second amplifier for amplifying said voltages, and means for connecting the output of said second amplifier to the input of said first-mentioned amplifier.

6. A sound recording system in accordance with claim 5 in which a phase and frequency characteristic adjusting network is connected between the output of said second amplifier and the input to said first-mentioned amplifier.
